UNITED STATES PATENT OFFICE.

GEORGE W. BEADLE, OF BAYONNE, NEW JERSEY, ASSIGNOR TO SINGLE SERVICE PACKAGE CORPORATION OF AMERICA, OF NEW YORK, N. Y., A CORPORATION OF NEW JERSEY.

CLOSURE FOR VESSELS.

1,031,615.

Specification of Letters Patent.

Patented July 2, 1912.

Application filed February 28, 1911. Serial No. 611,451.

To all whom it may concern:

Be it known that I, GEORGE W. BEADLE, a citizen of the United States, residing at Bayonne, in the county of Hudson and State of New Jersey, have invented certain new and useful Improvements in Closures for Vessels; and I do hereby declare the following to be a full, clear, and exact description of the invention, such as will enable others skilled in the art to which it appertains to make and use the same.

My invention relates to improved closures for vessels, and it consists in the constructions, combinations and arrangements herein described and claimed.

An object of my invention is to provide an improved closure which will provide a protective covering for the pouring lip of a vessel and prevent the accidental entrance of extraneous matter during removal of the closure, and which is adapted to be readily removed and replaced to permit successive removals of portions of the vessel's contents.

A further object of my invention is to provide a locking closure of fibrous material, such as paper, adapted to be positively clamped in locked position, and which provides an inexpensive closure adapted for efficient use with flexible vessels.

In the accompanying drawings forming a part of this application and in which corresponding reference symbols indicate similar parts in the several views:—

Figure 1 is an elevation, partly in section, illustrating one embodiment of my invention; Fig. 2 is a view similar to Fig. 1, showing the elastic, stretchable, annular apron snapped into inverted position for unclamping the closure; Fig. 3 is an enlarged detail section of the closure locking and clamping means; and, Fig. 4 is an enlarged detail section, illustrating the manner of removing the closure.

Referring to the drawings:—1 indicates a cylindrical vessel body of suitable material, having its edge, or pouring rim, 2 crimped inwardly to provide an annular locking shoulder 3.

A closure 4 of suitable fibrous, flexible material, such as paper, is shown comprising a flexible disk formed with a peripheral bead 5 of a diameter greater than the inner diameter of said annular shoulder 3, and adapted to be flexed into locking position

past said annular shoulder. An integral, 55 annular apron 6 extends from said bead 5 over the edge of the vessel and depends into close engagement with the exterior of said vessel for lockingly clamping the closure in position; this provides a very advantageous and efficient lock for preventing accidental displacement of the closure through yielding of its flexible disk, or, in the case of flexible vessels, through springing of the walls of the vessel. 65

My improved closure can be advantageously formed of paper of suitable toughness and flexibility, which is spun into its locked and clamped position upon the vessel, whereby the material is permanently set. This improved construction of fibrous, flexible material, provides an elastic, stretchable, annular clamping apron 6 which is adapted to be readily snapped without disruption into inverted position for unclamping said closure, as shown in Fig. 2; thereby enabling the closure to be readily removed and replaced for permitting successive removals of portions of the vessel's contents. 75

When the apron 6 has been thus snapped to unclamped position, the closure can be readily removed by pressing said apron inwardly to flex the closure disk for permitting withdrawal of the latter from its locked position past the locking shoulder 3. 85

It will be noted that my improved closure provides a protective covering for preventing contamination of the pouring lip of the vessel, and that the inverted annular apron provides a cup for entrapping any dirt 90 which may have collected on the closure. Further, the stretching of the elastic annular apron 6 in initially removing the closure will cause minute surface cracks in said apron, thereby clearly indicating that the 95 vessel has been opened.

I have illustrated preferred and satisfactory constructions, but changes could be made within the spirit and scope of my invention.

I claim:—

1. The combination of a vessel having an internal locking shoulder, and a closure provided with a locking member adapted to engage said shoulder, and with an integral, elastic, stretchable, annular apron adapted to closely fit the exterior of said vessel for lockingly clamping said closure 105

in position and to be readily snapped into inverted position for unclamping said closure.

2. The combination of a cylindrical vessel having an annular shoulder within its edge, and a closure of fibrous material provided with a flexible locking disk of a diameter greater than the interior diameter of said annular shoulder, and with an integral, 5 elastic, stretchable, annular apron adapted 10 to extend over said edge and depend into en-

gagement with the exterior of said vessel for lockingly clamping said closure in position and to be readily snapped into inverted position above said edge for unclamping said closure. 15

In testimony whereof, I affix my signature, in presence of two witnesses.

GEORGE W. BEADLE.
